RIBBON DISK FOR TYPEWRITERS

Ivan Gustaf Henry von Kraemer,
Stockholm, SwedenApplication February 2, 1946, Serial No. 645,091
In Sweden November 28, 1945

8 Claims. (Cl. 197—150)

1

This invention relates to the substitution of the writing-ribbon on a typewriter by a rotatable ribbon-disc. The ordinary typewriter ribbon is difficult to insert in the machine, some people finding it impossible to perform, and requiring assistance. It is expensive under ordinary usage, and due to these disadvantages there is a tendency to overuse the ribbon until the types have hammered it to rags, which tangle in the mechanism. Also the writing will sooner or later become indistinct, and will have empty spaces, and the ink will vanish, as it cannot be renewed.

My invention will overcome these objections by using a rotatable disc, which in one manipulation can be placed into position, or removed, the operation being so simple that any person, however unskilled, will be able to perform it.

As a result the complicated shifting mechanism, which easily becomes out of order, and which is used for pulling the ribbon from one side to another can be eliminated and the cost of manufacture of the typewriter can be considerably reduced. The ribbon-disc can be produced at a very low cost, and being made from any desirable resistant material, it will reduce the cost of typewriting to a considerable extent.

The invention is illustrated in the accompanying drawings, in which Fig. 1 is a side elevational view, and Fig. 2 is a top plan view.

On a thin disc 1, made from brass- or aluminum-plate, hard pasteboard or some other suitable material is glued, riveted or in some other way fastened a concentric, circular sheet, made from silk-cloth, nylon-fabric, rubber-sheet or other flexible but resistant material. This fabric-sheet protrudes over the disc 1, its outer edge running parallel with the periphery of the disc 1 and thus forming a ribbon 16, which is one of the main objects of the invention. The protruding concentric ribbon 16 is supplied with ink by a revolving inking-roller 8. The disc 1 is in its centre provided with a shaft, and on this shaft are pressed two flanges 2.

The part 6 is the modified sliding-fork, herein referred to as the ribbon-support used on the ordinary typewriter, serving to support and move the ink-ribbon up and down. Here it will serve to carry the disc 1 and move it up and down during writing. This part 6 is connected with a lever, and is operated up and down when any key is struck. It has a slot 9 in its middle and in this slot 9 the disc is lowered and kept in position by a small spring 14, pressing over the shaft between the flanges 2.

Instead of the ink-ribbon on the ordinary type-

2

writer, the concentric ribbon 16 is now moved up and down with each pressing of a type-key. On one part of the typewriter, supporting the pivots of the type bars, a rigid tongue 5 is fixed, intended as a guide or a carrier, on which the fork 6 is slideable up and down, small lugs at the edges of the tongue 5 being bent around onto the edges of the fork 6. In the centre of the tongue 5 is a slot 10 corresponding to the slot 9 in the fork. The slot 10 is wider, to enable the shaft and its flanges to move freely.

On the disc 1 is fixed a concentric cog-wheel 3. At the lower part of the rigid metal-tongue 5 a pawl 4 is screwed on, its upper end pressing against the cog-wheel. For each depression of a type-key the disc 1 is moved up and down, and therefore the pawl 4 will cause the disc 1 to revolve.

The fork 6 has at one side an extended arm 7 intended to support the axis 15 of the revolving inking-roller 8. This roller can be made in various ways, but its principle is to supply the ribbon with coloring matter.

On the upper end of the fork 6 two arms 11 are fixed, and supplied with joint-members 13 connected through the joints 12. These arms and their jointed prolongations will serve to steady and guide the ribbon 16. The joint-members 13 are intended to be bent down on the off-side of the ribbon 16.

Having now described my invention with its principle fully explained, what I desire protected with Letters Patent is set forth in the following claims:

1. A typewriter comprising a rotatable disc, a resistant ribbon secured to one face of said disc concentric therewith and overlapping the periphery of said disc, vertically movable means for supporting said disc and ribbon, and means for rotating said disc in response to its vertical movement by said supporting means.

2. A typewriter according to claim 1, in which the said means for rotating said disc includes a cog wheel and pawl.

3. A typewriter according to claim 1, in which the said vertically movable supporting means is a vertically movable sliding fork.

4. A typewriter according to claim 3, in which said sliding fork has a plurality of fixed arms for supporting and guiding said ribbon.

5. A typewriter according to claim 1, in which said vertically movable supporting means is a sliding fork having a slot, and the said disc carries a rotatable shaft having annular flanges for guiding said disc in its movement into said slot.

6. A typewriter according to claim 5, including a spring carried by said sliding fork for maintaining the said disc in a fixed vertical position with respect to the said slot.

7. A typewriter according to claim 6, including an inking roller rolling against said ribbon, and means carried by said sliding fork for supporting said inking roller.

8. A typewriter according to claim 7, in which the said means carried by said sliding fork comprises an arm.

IVAN GUSTAF HENRY VON KRAEMER.
